RADIATOR ORNAMENT

Joseph Fischer, New York, N. Y.

Application March 28, 1935, Serial No. 13,400

6 Claims. (Cl. 46—115)

My present invention relates generally to radiator ornaments and is particularly designed to be employed in connection with automobiles having attached to the radiator, a simple pre-existing ornament.

At the present time, many of the makes of automobiles are sold to the consumer having attached to the body of the car, a simple radiator ornament which is usually of a streamlined shape or configuration, or at least, which indicates such streamlining. My present invention aims to devise an attachment for such ornaments which will enhance their attractiveness and can be attached thereto by the ordinary purchaser by the use of simple every-day tools, and without the exercise of any skill on his part.

In the drawing, Fig. 1 represents a side elevational view showing the device of my present invention as attached to an automobile. Fig. 2 represents a section on the line 2—2 of Fig. 1. Fig. 3 represents a fragmentary side elevational and sectional view of an alternative form of the present invention. Fig. 4 is a fragmentary plan of the alternative form shown in Fig. 3.

At 5 is shown a radiator ornament which is affixed to the car by the manufacturer in the form in which it comes to the purchaser. The portion 6, is a section of this ornament which is usually designed to indicate streamlining or speed, and is generally of the shape shown in the drawing. 7 indicates generally my attachment, which consists of any figure 8 attached to the base 9. This base 9, is hollow inside at 10, and has a stop at one end 11 to prevent the same from sliding too far along the portion 6.

At 12 is shown a means for affixing my attachment which may be done either by means of the set screws in Fig. 2, or the bolt 12a as shown in Figs. 3 and 4. Of course in manufacturing my attachment, it is advisable to have the configurations of the base 9, conform to the configurations of the portion 6, so that a snug fit may be obtained.

It is of course understood, that the foregoing is set forth solely by way of illustration, and various changes may be made without departing from the spirit of the invention or the scope of the claims.

What I claim as my invention is:

1. As an article of manufacture, an attachment for a radiator ornament comprising a base member and an ornamental design member, said base member containing a substantially hollowed out inverted substantially V-shaped portion

adapted to cooperate with the radiator ornament proper.

2. In combination with an existing automobile radiator ornament, an auxiliary ornament having a base member and an ornamental design member, said base member being adapted to slidably cooperate with and substantially conceal the existing radiator ornament, whereby the existing radiator ornament forms a portion of the base of the combination.

3. In combination with an existing automobile radiator ornament, an auxiliary ornament having a base member and an ornamental design member, said base member being adapted to slidably cooperate with and substantially conceal the existing radiator ornament, whereby the existing radiator ornament forms a portion of the base of the combination, the exterior portion of the base member being a substantial replica of the concealed portion of the existing radiator ornament.

4. In combination with an existing automobile radiator ornament, an auxiliary ornament having a base member and an ornamental design member, said base member being adapted to slidably cooperate with and substantially conceal the existing radiator ornament, whereby the existing radiator ornament forms a portion of the base of the combination, and a plurality of means for retaining the auxiliary ornament in an engaged position.

5. In combination with an existing automobile radiator ornament, an auxiliary ornament having a base member and an ornamental design member, said base member being adapted to slidably cooperate with and substantially conceal the existing radiator ornament, whereby the existing radiator ornament forms a portion of the base of the combination, and a plurality of means for retaining the auxiliary ornament in an engaged position, said means including a screw at one end and a stop at the other.

6. In association with a standard ornament for an automobile, a supplemental ornament adapted to be mounted upon said standard ornament, comprising an upper portion in the form of a desired ornament, a base portion integral with said upper portion, said base portion having a substantially U-shaped transverse cross-section to enable it to fit over and conform to the upper part of said standard ornament, and means cooperating with said base portion and said standard ornament to secure said supplemental ornament on said standard ornament.
